UNITED STATES PATENT OFFICE.

EMANUEL SPITZER, OF MUNICH, GERMANY, ASSIGNOR OF TWO-FOURTHS TO
MRS. ALPHA O. GOLDSMITH, OF BERLIN, GERMANY, AND ONE-FOURTH
TO SOPHIE SPITZER, OF MUNICH, GERMANY.

PROCESS FOR PRODUCING PRINTING-PLATES.

No. 845,138.

Specification of Letters Patent.

Patented Feb. 26, 1907.

Application filed July 7, 1902. Serial No. 114,682. (Specimens.)

To all whom it may concern:

Be it known that I, EMANUEL SPITZER, 5
kunstmaler, a citizen of the Empire of Austria, residing at Munich, Bavaria, Germany, 10
have invented certain new and useful Improvements in Processes for Producing Printing-Plates; and I do hereby declare the following to be a full, clear, and exact description of the invention, such as will enable others skilled in the art to which it appertains 15
to make and use the same.

My invention relates to the art of making printing-plates, and in particular to the manufacture of photomechanical printing plates or surfaces.

The object of this invention is to produce printing-plates by photomechanical methods directly from continuous photographic plates or films produced by light, X, or Becquerel 20 or other rays—that is, without the use of screens or other artificial stippling steps.

The characteristic feature of the invention consists in the fact that a photographic plate is directly—that is, without the use of 25 screens or other artificial stippling steps—copied onto the plate to be etched provided with a sensitive layer, the copy then subjected to the influence of an etching agent and the etching allowed to take place, the result being 30 an etched plate with minute cavities and between them minute elevations or stippling massed so as to correspond to the different shade and light values of the original and representing the same in all its finest details 35 in a most perfect manner.

The following example illustrates what I consider a preferable manner of carrying out my invention. I coat a polished printing-plate in the manner well known with a coating 40 of sensitive solution, such as chrome-glue or gelatin solution, as used in the art. It is important to dry this coating as uniform and as free from grain as possible. This may, for instance, be effected by rotation and 45 simultaneous warming on a centrifugal apparatus or the like. I then expose the plate directly—that is, without interposing a screen or the like—to the light under a continuous negative (film or glass)—that is to 50 say, a negative which represents no linework. The time of exposure varies according to the density of the photographic plate and the character of the light used. An exposure of

from five to fifteen minutes will generally be found sufficient. Care should now be taken 55 that the condition which the sensitive coating has obtained by its exposure to light, what we may call its "graduated hardening," and with it its graduated permeability to acids and corresponding etching capability 60 in the details, is not impeded or destroyed by such manipulations as melting on it asphalt-dust or the like or by enameling or other procedures liable to destroy the above-mentioned properties of the coating after its exposure to light. The plate to be etched, 65 with the copy obtained thereon, is then immersed into the etching-bath and the etching allowed to take place until the whole picture appears etched, even in the finest 70 details. The strength or concentration of the etching-bath is that usually employed in etching processes of this character, and where a bath of chlorid of iron, ($FeCl_3$), which gives good results with a plate prepared as above, is employed the strength of 75 the same varies between 30° and 48° Baumé. According to the nature of the subject and of the detail and shading thereof, several etching-baths of different degrees 80 of concentration may be employed, as will be understood by those skilled in the art. The temperature of the etching agent and the selection of the same are matters which are governed largely by the various conditions 85 of the work and are matters of detail which, as well as in general all the different manipulations, procedures, and materials used in this process, those skilled in the art will readily select.

I find that it is better during the etching process not to brush away or shake out the deposits formed by the etching agent on the plate, as they form the best protection against any injury of the finest parts in the further 95 etching process.

By keeping the sensitized coating in its condition of graduated hardening, and thereby graduated permeability to acids, as before mentioned, a correspondingly-graduated etching takes place, the various points or stippling in consequence of a partial etching off of their tops lying in different levels, so that in printing the taking of and giving off the printing-ink will be graduatedly stronger 100 in the intaglio (plate-printing) process or

graduatedly fainter in the relief-printing process.

After the etching operation is completed as above the plate is removed from the etching-bath and cleaned in the usual manner and is then ready for printing. The partial etching off of the printing elements before mentioned so characteristic for the present process may be kept, according to the purpose in view, stronger or lighter or even so delicate as not to be seen by the naked eye and only under the microscope, and yet it will be effective in printing.

The plates etched according to this method may be used for the typographical printing-press relief-printing as well as for plate-printing, intaglio. For plate-printing purposes of course a diapositive has to be employed instead of a negative, as used for the relief-printing process.

The direct copy of the photographic plate or film onto the plate to be etched in connection with the above-described manner of directly etching insures the highest perfection of the reproduction in the various kinds of printing and at the same time renders the reproduction considerably cheaper and more easy to make.

Obviously this process may be employed also for ornamenting surfaces and plates of metal or other material and for making signs and the like.

The relief and intaglio plates hereinbefore described as the product of the present invention are not herein claimed, since they are separately covered in my concurrent applications, Serial No. 232,761, (No. 5,) and Serial No. 232,762, (No. 6,) filed November 14, 1904.

Having thus described my invention, what I claim as new, and desire to secure by Letters Patent, is—

1. In the art of producing photomechanical printing-plates, the process which consists in exposing a plate provided with a sensitized film under an ordinary continuous negative or diapositive and without the in-

terposition of a screen, and then etching such plate without any manipulation or procedure liable to interfere with the property of said film to resist in its graduatedly-hardened parts the action of an etching fluid in graduated degrees.

2. In the art of producing photomechanical printing-plates, the process which consists in exposing a plate provided with a smooth ungrained sensitized coating under an ordinary continuous negative or diapositive and without the interposition of a screen, and then submitting such plate to an etching agent without the application of any etching resist to the sensitized coating.

3. In the art of producing photomechanical printing-plates, the process which consists in exposing a plate provided with an ordinary sensitized coating under an ordinary continuous negative or diapositive and without the interposition of a screen, etching said plate, and leaving the deposits, formed by the etching action, on the plate until the end of the etching operation.

4. In the art of producing photomechanical printing-plates, the process which consists in exposing a plate provided with a smooth ungrained sensitized coating under an ordinary continuous negative or diapositive and without the interposition of a screen, etching said plate and leaving the deposit from the etching agent on the plate.

5. The process of producing photomechanical printing-plates, which consists in exposing a plate coated with a layer of bichromatized gelatin under an ordinary continuous negative without the interposition of a screen, then immersing such plate into an etching-bath without the prior application of any etching resist and leaving the deposits from the etching-bath on the plate.

In testimony whereof I affix my signature in presence of two witnesses.

EMANUEL SPITZER.
